(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is a front view of a second embodiment thereof. The broken lines around the Figures showing a display screen or portion thereof form no part of the claimed design. The broken lines within the Figures show portions of the graphical user interface which form no part of the claimed design.

UNITED STATES PATENT AND TRADEMARK OFFICE
CERTIFICATE OF CORRECTION

PATENT NO. : D692,910 S
APPLICATION NO. : 29/412663
DATED : November 5, 2013
INVENTOR(S) : Anzures et al.

Page 1 of 4

It is certified that error appears in the above-identified patent and that said Letters Patent is hereby corrected as shown below:

Delete Title Page, and replace with new Title Page, attached.

Title Page, item (57), DESCRIPTION section, line 2,

please change "and," to -- and --.

In the Drawings:

Replace Figures 1 and 2 with the attached Figures 1 and 2.

Signed and Sealed this
Twenty-fifth Day of February, 2014

Michelle K. Lee
Deputy Director of the United States Patent and Trademark Office
